Primary Examiner — Paula Allen Greene(74) *Attorney, Agent, or Firm* — Beeson Skinner Beverly, LLP(57) **CLAIM**

The ornamental design for a loudspeaker grille as shown and described.

DESCRIPTION

FIG. 1 is a front perspective view of loudspeaker grille showing our new design;

FIG. 2 is an enlarged front perspective view thereof;

FIG. 3 is a front elevational view thereof;

FIG. 4 is a left side elevational view thereof;

FIG. 5 is a right side elevational view thereof; and,

FIG. 6 is a top plan view thereof.

The broken lines depict portions of the loudspeaker grille that form no part of the claimed design.
